WELL TOOL

Ora A. Brown, South Gate, Calif., assignor to
 Baash-Ross Tool Company, Los Angeles, Calif.,
 a corporation of California

Application June 5, 1934, Serial No. 729,097

16 Claims. (Cl. 164—0.4)

This invention relates to a well tool and it is a general object of the invention to provide a simple, practical and effective well tool involving an improved means for gripping the interior of a pipe or casing to provide for the actuation of the other parts or mechanisms of the tool.

In various well tools such as perforators, etc., the cutters are controlled or actuated by relative movement between the parts of the tools. The tools are operated in the wells on the lower ends of strings of pipe or the like and, therefore, are rather difficult to control. It has been the general practice to provide a tool of the general character referred to with a tail piece having springs 10 for frictionally engaging the interior of the pipe or well casing, whereby relative movement between the parts of the tool may be effected to actuate the cutter. The springs of a tail piece are only capable of yieldingly resisting movement 20 and do not assure the full proper operation of the tool.

Another object of the invention is to provide a well tool having means for firmly and securely engaging the interior of a casing or pipe in which 25 the tool is operated, whereby the required relative movement may be effected between the parts of the tool to fully and properly actuate it.

Another object of the invention is to provide a well tool including a slip that may be easily and 30 quickly actuated into dependable gripping engagement with the interior of a casing and that is automatically released when it has served the desired purpose.

Another object of the invention is to provide a well tool including a gripping slip that is adapted to tightly grip the interior of a pipe or 35 casing and that is provided with an inclined face engaged by a cutter when the tool is moved through the casing to actuate the cutter into engagement with the casing.

A further object of this invention is to provide a well tool of the character mentioned that involves a novel and particularly effective combination of parts and that is simple and inexpensive 40 of manufacture.

Other objects and features of the invention will become apparent from the following detailed description of a typical form and application of the invention, throughout which description reference may be had to the accompanying drawings, in which:

Fig. 1 is a side elevation of a well tool embodying the present invention showing it passing through a casing. Fig. 2 is an enlarged longitudinal detailed sectional view of the upper por-

tion of the tool showing the slip and cutter in the retracted positions. Fig. 3 is an enlarged longitudinal detailed sectional view of the lower portion of the tool illustrating the tail piece assembly in position for passage downwardly through the casing. Fig. 4 is an enlarged longitudinal detailed sectional view of the central or intermediate portion of the tool showing the cutter in a substantially fully actuated position and illustrating the cutter in broken lines in the fully actuated position. Figs. 5, 6, and 7 are enlarged transverse detailed sectional views taken as indicated by lines 5—5, 6—6 and 7—7, respectively, on Fig. 2 and Fig. 8 is an enlarged transverse detailed sectional view through the upper portion 15 of the body illustrating the cutter in the body channel.

Certain features of my invention are suitable for embodiment in well tools varying considerably in character. In the following detailed disclosure 20 I will describe the invention embodied in a perforator for forming or cutting perforations in a well casing, it being understood that the invention is not to be construed as limited or restricted to the specific form or application about to be 25 described, but that it is to be taken as including any features or modifications that may fall within the scope of the claims.

The well tool illustrated in the drawings and embodying the invention includes, generally, a 30 body 10, a cutter 11 carried by the body and operable outwardly upon movement of the body with respect to it, a slip 12 for gripping the casing C and engaged by the cutter 11 to cause its actuation, and means 13 for controlling the actuation 35 of the slip 12.

The body 10 is an elongate member or structure adapted to be operated on the lower end of an operating string S of pipe or the like. Suitable means is provided at the upper end of the body 10 for connecting with the string S. In the particular structure illustrated in the drawings a tapered screw-threaded pin 14 is provided on the upper end of the body 10 for threading into a socket in the lower member of the string S. The body 10 is in the nature of a frame or carrier for the various parts of the tool and is provided with a longitudinal open-sided opening or channel 15. A channel member 16 is arranged longitudinally in the channel 15. The inner side of the member 16 bears against the inner wall of the channel 15 while the spaced side flanges 17 of the member bear against the side walls of the channel. A block 18 is arranged in the upper end of the body channel 15 and screws 19 pass through open- 55

ings in the block and member 16 and thread into the body 10 to attach the member to the body. The lower portion of the body channel or opening 15 is in the nature of a slot passing through the body from one side to the other. The channel member 16 has a key 20 on its rear side fitting the slotted portion of the body and having its upper end cooperating with a downwardly facing shoulder 21 of the body.

10 In accordance with the invention two curved convex surfaces 22 and 23 are provided in the lower portion of the channel member 16. The lower convex surface 22 curves upwardly and inwardly from the rear external surface of the member 16 and is exposed below the lower ends of the flanges 17. The upper convex surface 23 is disposed between the spaced flanges 17 and joins or forms a continuation of the inner wall of the channel member 16. The convex surface 20 22 is cylindrically curved about a point A while the convex surface 23 is curved about a point B. The surface 23 has a radius of curvature substantially the same as that of the surface 22 and its point of curvature B is spaced upwardly and inwardly from the point A relative to the central longitudinal axis of the tool. The outer surfaces or sides of the flanges 17 have portions 24 curved about the axis B and continue downwardly and rearwardly from these portions 24 to the rear 25 external surface of the tool. Ribs or flanges 25 are provided on the opposite side walls of the body channel 15 and are spaced outwardly from the outer sides of the flanges 17. The opposing surfaces of the flanges 17 and 25 are spaced and 30 parallel to provide longitudinally extending keyways 26. The flanges 25 may be welded or otherwise attached to the body 10. The inner sides of the flanges 25 each have a concave surface 26a curved about the point B and a concave surface 40 27 curved about the point A.

The cutter 11 is operable outwardly to perforate the casing C through cooperation with the surfaces 22 and 23 and cooperates with the slip 12 to aid in the actuation of the slip and to bring about the initial portion of its own actuation. The cutter 11 includes a shank 28 and a blade 29. The shank 28 has flat parallel sides 30 adapted to slidably engage the inner sides of the flanges 17 and 25. Keys 31 are provided on the sides 30 45 of the cutter shank for operating longitudinally in the keyways 26. When the cutter 11 is in its normal retracted position illustrated in Fig. 2 of the drawings the keys 31 are substantially horizontal and their ends 32 engage or have slight clearance with the concave surfaces 27 of the flanges 25. These ends 32 of the keys may have a radius of curvature slightly shorter than that of the surfaces 27.

Two contiguous or adjacent concave surfaces 60 33 and 34 are provided on the inner side of the shank 30 for cooperating with the surfaces 22 and 23, respectively. The lower concave surface 33 has substantially the same radius of curvature as the surface 22 to effectively slidably operate over the surface 22. In a like manner the upper concave surface 34 has a radius of curvature substantially equal to that of the convex surface 23 to slidably operate over that surface. It will be seen that when the concave surface 33 slidably operates over the convex surface 22 the cutter 11 pivots or swings about the axis A and when the surface 34 moves over the surface 23 the cutter pivots or swings about the axis B. A straight flat face 35 is provided on the inner side of the shank 30 at the upper end of the concave surface

34. The flat face 35 is parallel with the keys 31 and is adapted to slidably operate on the inner wall of the channel member 16 when the cutter 11 has assumed its operated position in the straight upper portion of the channel member. 5

The blade 29 of the cutter 11 is of reduced thickness and projects downwardly in the body channel or slot 15 when the cutter is in its retracted or unactuated position. The blade 29 has a curved lower edge 36 and a straight outer edge 10 37 adjoining the edge 36 at a point or corner 38. The upper edge 39 of the blade joints the outer edge 37 at a corner 40.

The slip 12 is provided to engage or grip the casing C to form a bridge or abutment for the cutter 11 whereby the cutter may be swung about the axis A upon downward movement of the body 10 through the casing. The slip 12 is arranged in the open or slot portion of the body channel 15 and is shiftable longitudinally and laterally 20 with respect to the body. The slip 12 has flat parallel sides 41 for slidably engaging the side walls of the body opening 15. The outer side of the slip 12 is adapted to project from the body 10 to engage the interior of the casing C and is provided with a series of serrations or teeth 42. The teeth 42 are designed or shaped to effectively grip the inner wall of the casing C to resist or prevent downward movement of the slip 12. The upper end 43 of the slip 12 is inclined downwardly 30 and outwardly to the toothed outer surface of the slip. This inclined upper end 43 of the slip cooperates with the curved lower edge 36 of the cutter 11 so that downward force may be transmitted from the cutter to the slip when the tool 35 is moved downwardly to bring about the actuation of the slip 12 as will be hereinafter described. Further, the engagement of the lower edge of the cutter 11 with the inclined upper end 43 of the slip holds the cutter against downward 40 movement after actuation of the slip and causes the cutter to swing or turn about the axis A with the downward movement of the body. The inner side 44 of the slip 12 is inclined in the same general direction as the surface 43. In practice 45 the inner side 44 of the slip may be at a greater pitch or inclination than the upper end of the slip. The lower end of the slip 12 normally rests or seats on a shoulder 45 of the body and the lower edge of the retracted cutter 11 normally 50 cooperates with the inclined upper end 43 of the slip. With the slip 12 in the position just mentioned its teeth 42 are retracted within the confines of the body 10 so that they cannot engage the casing C. 55

The means 13 for controlling or actuating the slip 12 causes outward projection of the slip 12 into gripping engagement with the casing C whereby the slip forms a bridge or abutment for the cutter 11 when the cutter is actuated. The means 13 includes a wedge block 47 in the lower portion of the body channel or slot 15. The block 47 has its rear side flush with the external rear surface of the body 10 and has a shoulder 48 normally cooperating with a shoulder 49 of the body. A wedge face or inclined surface 50 is provided on the block 47 for slidably cooperating with the inclined inner side 44 of the slip. The surface 50 is of the same inclination as the surface 44 and is of substantial length. In the preferred form of the invention a dove-tail sliding connection is provided between the slip 12 and the block 47. In the form of the invention illustrated the dove-tailed connection includes a dove-tailed key 52 on the inclined inner side of the 75

slip slidably operating in a correspondingly shaped keyway 53 in the surface 50. The block 47 is arranged or mounted for longitudinal movement with respect to the body and has a stem or shank 54 slidable in an opening 56 in the body. The wedge block 47 is normally in a position where its shoulder 48 cooperates with the body shoulder 49 which position is illustrated in Fig. 2 of the drawings.

10 The means 13 includes a tail piece 57 for controlling the operation of the wedge block 47 and the slip 12. The tail piece 57 includes a mandrel or stem 58 slidable in a reduced portion 59 of the opening 56 in the lower end of the body 10. 15 The stem 58 is connected with the shank 54 of the wedge block 47. In the particular structure disclosed in the drawings the stem 58 has a reduced portion threaded into a socket 60 in the lower end of the shank 54 and keyed against 20 displacement by a key 61. The stem 58 has an enlargement or collar 70 operating in a socket 71 in the lower end of the opening 59. The longitudinal axis of the opening 59 and the longitudinal axis of the stem 58 are offset or spaced 25 from the longitudinal axis of the body 10. The axis of the opening 59 and the stem 58 are offset from the axis of the body in the direction of the forward side of the body 10 and slip 12 so that the tail piece assembly is substantially centered in 30 the casing when the engagement of the slip 12 with the casing moves the tool out of its central position in the casing.

The stem 58 projects a substantial distance from the lower end of the body 10 and carries at 35 its lower end a bull nut 62. Longitudinally spaced sleeves 63 and 64 are slidable on the stem 58 and are connected by spaced springs 65. The springs 65 are bowed outwardly to frictionally engage the interior of the casing C. The engagement of the springs 65 with the inner wall of the casing C resists movement of the tail piece assembly with respect to the casing. Latch means is provided for releasably connecting the assembly of the sleeves and springs with the stem 58. 45 A latch 66 has its upper end pivoted in a longitudinal recess 67 in the lower portion of the stem 58. The latch 66 has a downwardly facing shoulder 68 adapted to cooperate with the upper end of the sleeve 64. A spring 69 yieldingly urges 50 the latch 66 outwardly.

When the tool is to be run or lowered into the well the tail piece assembly of the springs 65 and sleeves 63 and 64 is slid on the stem 58 to a position such as illustrated in Figs. 1 and 3 of the drawings, where the upper sleeve 63 is contacting the lower end of the body 10 and the lower sleeve 64 covers the upper portion of the recess 67 to hold the latch 66 in a partially retracted position. As the tool is run into the well on the lower end of the operating string S the springs 65 frictionally engage the inner wall of the casing C to hold the tail piece assembly in the position just described. The weight of the stem 58, the bull nut 62, and the wedge block 47 retains the wedge 65 block in the position where its shoulder 48 seats on the shoulder 49. With the wedge block in this position during lowering of the tool into the well the sleeve 12 and the cutter 11 are in their retracted positions illustrated in Fig. 2 of the drawings.

When the tool has reached the required depth it is raised or moved upwardly through the medium of the operating string S. This upward movement of the tool causes the stem 58 to be moved 75 upwardly with the body 10 moving the latch 66

through the sleeve 64 and bringing the bull nut 62 to a position at or adjacent the lower end of the sleeve 64. With the parts in the raised position just described the latch 66 is yieldingly held in its out position where the shoulder 68 opposes and/or engages the upper end of the sleeve 64. The tool is then lowered or moved downwardly to actuate the slip 12 and the cutter 11. During this downward movement of the tool the springs 65 of the tail piece resist downward movement of the stem 58 and wedge block 47, the stem being connected with the spring assembly by the latch 66. The cooperation of the convex surface 22 with the concave surface 33 of the cutter 11 causes the cutter to move downwardly with the body and the lower edge 36 of the cutter contacts the inclined surface 43 of the slip to transmit this downward movement to the slip. The slip 12 is thus moved downwardly on the inclined surface 50 of the wedge block which is held 20 against movement or restrained from movement by the springs 65 as described above. The co-operation of the surfaces 44 and 50 of the slip and the wedge block cause the slip 12 to move outwardly so that its teeth 42 come into gripping 25 engagement with the interior of the casing C. The slip 12 is thus positively held against downward movement and the rear surfaces of the body 10 and the wedge block 47 are forced laterally against the opposite walls of the casing 12. The 30 slip 12 and the wedge block 47 constitute a fixed bridge, the slip forming a stationary abutment against which the cutter 11 operates.

The cutter 11 moving downwardly together with the body 10 has its curved edge 36 engaging 35 the inclined surface 43 of the slip 12 and is made to swing or pivot about the point A. It is believed that it will be understood how the convex surface 22 of the downwardly moving body 10 cooperates with the concave surface 33 of the 40 cutter to cause the cutter to be swung outwardly from the body about the axis or point A. In this manner the cutter is projected into cutting or perforating contact with the casing C. The cutter 11 will have been operated into biting or cutting 45 engagement with the casing C before the upper wall of the socket 71 in the downwardly moving body 10 contacts the upper end of the collar 70 on the tail piece stem 58. Engagement of 50 the upper end of the socket 71 with the collar 70 causes the stem 58 to be moved downwardly with the body and as the block 47 is attached to the stem it is also made to move downwardly with the body. The biting engagement of the teeth 42 with the casing C momentarily holds the 55 slip 12 against downward movement with the wedge block 47 so that the cooperation of the dove-tailed key 52 with the keyway 53 causes the slip to move upwardly on the inclined face 50 of the wedge block. In this manner the slip 12 is 60 retracted and fully disengaged from the casing C to move downwardly together with the wedge block and the body 10. Prior to this releasing of the slip 12 the cutter 11 has obtained an engagement with the casing C which prevents it 65 from moving downwardly with the body 10. The corner or point 40 of the cutter 11 having entered the wall of the casing holds the end of the cutter against movement whereby the surface 22 of the downwardly moving body causes the cutter 11 70 to swing about the axis A to a position where its concave surface 33 engages the convex surface 23 of the body. The convex surface 23 of the downwardly moving tool cooperates with the concave surface 34 to cause the cutter 11 to be swung 75

about the point B, thus further projecting its blade 29. The cutter 11 moves or swings about the axis B until its surface 35 engages the inner wall of the channel member 16, whereupon the 5 keys 31 assume a position in longitudinal alignment with the keyways 26. The body is then freed to move downwardly with little or no resistance offered to its movement by the cutter, as the cutter is freely received in the elongate 10 channel member 16. This relieving of resistance to downward movement of the tool informs the operator that the cutter 11 has been fully actuated. The tool may then be raised so that the convex surfaces 23 and 22 cooperate with the 15 concave surfaces 34 and 33 of the cutter to swing the cutter inwardly to its retracted position. The tool may then be moved to another position in the casing and again operated if desired, or the tool may be removed from the well.

20 The present invention provides a well tool that embodies a slip member which firmly and dependably grips the interior of the casing to form a rigid or stationary abutment for the positive actuation of the cutter. The slip 12 together with 25 the wedge block 47 forms a stationary bridge in the casing as the body 10 moves downwardly with the cutter, whereby the cutter cooperating with the inclined surface 43 of the slip is positively operated into engagement with the casing C. The slip 12 is automatically disengaged from the casing after the cutter 11 has obtained a suitable engagement with the casing. The slip 12 cannot bind or permanently lock in engagement with the casing C as the dove-tailed connection between the slip and the wedge block operates to 30 fully free the slip from the casing. The well tool construction provided by the present invention is simple and particularly effective in operation.

35 40 Having described only a typical preferred form and application of my invention, I do not wish to be limited or restricted to the specific form and application herein set forth, but wish to reserve to myself any modifications or variations that 45 may appear to those skilled in the art or fall within the scope of the following claims:

Having described my invention, I claim:

1. In a well tool, a body, two members carried by the body and having slidably cooperating inclined surfaces, one member being toothed to grip the casing, a cutter carried by the body to engage said member and to swing into engagement with the casing upon movement of the body with respect to said member, and means for resisting movement of the other member whereby movement of the body results in cooperation of said surfaces to bring the toothed member into stationary engagement with the casing.
2. In a well tool, a body, two members carried by the body and having slidably cooperating inclined surfaces, one member being toothed to grip the casing and having an inclined face, a cutter carried by the body to engage said face and be swung outwardly through cooperation therewith upon longitudinal movement of the body, and means for resisting longitudinal movement of the other member whereby longitudinal movement of the body causes actuation of the toothed member and the cutter.
3. A well tool including a body adapted to move through a casing, two members having cooperating dove-tailed surfaces, one member being toothed to grip the casing, a cutter carried by the body and cooperating with the toothed member 75 to transmit movement thereto upon longitudinal

movement of the body, and means for temporarily resisting movement of the other member whereby longitudinal movement of the body causes actuation of the toothed member into gripping engagement with the casing followed by actuation of the cutter and then release of the toothed member from the casing.

4. In a well tool, a body, a cutter carried by the body, parts on the body and cutter operable to cause projection of the cutter from the body when 10 resistance is offered to vertical movement of the cutter, a gripping slip having an inclined surface engageable by the cutter, and means for actuating the slip into engagement with the casing by force transmitted to it by the cutter upon longitudinal 15 movement of the body whereby such movement actuates the cutter.

5. In a well tool, a body, a cutter carried by the body, parts on the body and cutter operable to cause projection of the cutter from the body when 20 resistance is offered to vertical movement of the cutter, a member carried by the body for limited relative longitudinal movement and having an inclined surface, a slip engaging said surface and engageable by the cutter to be actuated into 25 gripping engagement with the casing through cooperation with said surface by force transmitted to it from the cutter when the cutter is moved downwardly with the body, the cutter being projected by engaging the set slip, and means for 30 releasing the slip from the casing.

6. In a well tool, a body, a cutter carried by the body, means for projecting the cutter from the body operable by relative longitudinal movement between the cutter and the body, a member carried by the body for limited relative longitudinal movement and having an inclined surface, a slip engaging said surface and engageable by the cutter to be actuated into gripping engagement with the casing through cooperation with said surface 40 35 by force transmitted to it from the cutter when the cutter is moved downwardly with the body, the said means being actuated when the engagement of the cutter with the set slip resists longitudinal movement of the cutter, and means for releasing 45 the slip from the casing, the last named means including a sliding dove-tailed connection between the member and slip.

7. A well tool including a body, a member for acting on the well casing and initially retracted 50 in the body, means for projecting the member from the body upon movement of the body with respect to it, a casing gripping slip operable to grip the casing to form a stationary abutment for holding the member against movement with the body whereby movement of the body in one direction actuates the said means to project the member, means for actuating the slip into engagement with the casing upon movement of the body in said direction, and means for releasing the slip 60 from the casing upon further movement of the body in said direction, the last mentioned means including an element connected with the slip and having limited movement with respect to the body, and movement resisting means connected 65 with said element.

8. A well tool including a body, a cutting member carrier by the body for projection therefrom, and means for projecting the member upon longitudinal movement of the body with respect to 70 it, including two cooperating wedge members operable through their cooperation to have stationary engagement with the interior of a casing at circumferentially spaced points to form an abutment to be engaged by the cutting member 75

to hold the cutting member against longitudinal movement with the body, one of the wedge members being bodily movable laterally against the well casing whereby longitudinal movement of the body causes projection of the cutting member.

9. A well tool including a body, a member carried by the body and projectable therefrom to act on the casing, means for projecting the member from the body upon movement of the body with respect to it, a casing gripping slip for holding the member against movement with the body whereby movement of the body in one direction actuates the member, means for actuating the slip into stationary engagement with the casing upon movement of the body in said direction to form a stationary abutment against which the member is moved to be actuated, and means for releasing the slip from the casing upon further movement of the body in said direction.

10. In a well tool, a body adapted to be moved through a casing, a member for acting on the casing and related to the body for projection therefrom, means for projecting the member from the body upon movement of the body relative to the member, a casing gripping slip carried by the body for lateral movement therefrom into gripping engagement with the casing and having an inclined surface adapted to form an abutment to hold the member against movement with the body and to assist in projection of the member, and an inclined abutment on the body cooperating with the slip to actuate the same laterally against the casing.

11. In a well tool, a body adapted to be moved through a casing and having an opening open at its opposite sides, an assembly of two translatable members carried by the body and movable through said opening to have gripping engagement with the interior of the casing, cooperating inclined surfaces on the members operable to bodily shift the members against the casing upon relative vertical movement between the members, and means for shifting one member relative to the other to effect cooperation of said surfaces.

12. In a well tool, a body adapted to be moved through a casing and having a lateral opening open at its opposite sides, an assembly of two members carried by the body and movable outwardly through said opening to have gripping engagement with the interior of the casing, cooperating inclined surfaces on the members operable to actuate the members against the casing upon relative vertical movement between the members, a second inclined surface on one member, and an element adapted to cooperate with said second inclined surface to move one member relative to the other and to be actuated against the casing by such cooperation.

13. In a well tool, a body adapted to be moved through a casing and having an opening open at its opposite sides, an assembly of two members

carried by the body and movable through the ends of said opening to have gripping engagement with the interior of the casing, cooperating inclined surfaces on the members operable to actuate the members against the casing upon relative vertical movement between the members in one direction, means for effecting relative movement between the members in said direction, a dove-tail connection between the members, and a shoulder on the body adapted to cooperate with one member to effect relative movement between the members in the other direction to release them from the casing when the body is moved in the said other direction.

14. In a well tool, a body adapted to be moved through a casing and having an opening open at its opposite sides, an assembly of two members carried by the body and movable through the ends of said opening to have gripping engagement with the interior of the casing, cooperating inclined surfaces on the members operable to actuate the members against the casing upon relative vertical movement between the members in one direction, means for effecting relative movement between the members in said direction, a dove-tail connection between the members, a shoulder on the body adapted to cooperate with one member to effect relative movement between the members in the other direction to release them from the casing when the body is moved in the said other direction, and means connected with the other member to resist movement of the same.

15. In a well tool including a body, a member for acting on the casing and initially carried by the body in a retracted position, means for projecting the member from the body upon longitudinal movement of the body with respect to it, a slip for gripping the casing and adapted to form an abutment engageable by the member to hold the member against longitudinal movement with the body, and a control for the slip, the control including an element connected with the slip and having limited movement with respect to the body, and movement resisting means connected with the element.

16. A well tool including a body adapted to be moved through a casing, a member for acting on the casing and normally movable with the body in a retracted position, means for projecting the member upon longitudinal movement of the body with respect to the member, and an assembly of two cooperating casing gripping elements shiftably carried by the body adjacent said member so that one element may be engaged by the member, said elements being operable into gripping engagement with the casing through their cooperation to form an abutment which holds the member against longitudinal movement with the body.

ORA A. BROWN.
